US00D646582S

(12) **United States Design Patent**
Ren et al.

(10) **Patent No.:** **US D646,582 S**
(45) **Date of Patent:** **** Oct. 11, 2011**

(54) **PACKAGE**

(75) Inventors: **Wei Ren**, Beijing (CN); **Cesar Alejandro Jaramillo Lopez**, Guangzhou (CN)

(73) Assignee: **The Procter & Gamble Company**, Cincinnati, OH (US)

(**) Term: **14 Years**

(21) Appl. No.: **29/377,873**

(22) Filed: **Oct. 27, 2010**

(51) LOC (9) Cl. **09-01**

(52) U.S. Cl. **D9/651**; D9/432

(58) Field of Classification Search D9/600, D9/651, 667, 414, 430-433; 206/457-458, 206/527; 220/890

See application file for complete search history.

(57) **CLAIM**

The ornamental design for a package, as shown and described.

DESCRIPTION

FIG. 1 is a perspective view of a package, embodying our new design;

FIG. 2 is a front view thereof;

FIG. 3 is a back view thereof;

FIG. 4 is a right side view thereof;

FIG. 5 is a left side view thereof;

FIG. 6 is a top plan view thereof;

FIG. 7 is a bottom view thereof;

FIG. 8 is a perspective view of a second embodiment of a package, embodying our new design;

FIG. 9 is a front view thereof;

FIG. 10 is a back view thereof;

FIG. 11 is a right side view thereof;

FIG. 12 is a left side view thereof;

FIG. 13 is a top plan view thereof;

FIG. 14 is a bottom view thereof;

FIG. 15 is a perspective view of a third embodiment of a package, embodying our new design;

FIG. 16 is a front view thereof;

FIG. 17 is a back view thereof;

FIG. 18 is a right side view thereof;

FIG. 19 is a left side view thereof;

FIG. 20 is a top plan view thereof; and,

FIG. 21 is a bottom view thereof.
